UNITED STATES PATENT OFFICE.

SEM ROSENTHAL, OF NEW YORK, N. Y.

CABINET.

Application filed August 5, 1924. Serial No. 730,267.

To all whom it may concern:

Be it known that I, SEM ROSENTHAL, a subject of Great Britain, residing at New York city, in the county of New York and 5 State of New York, have invented new and useful Improvements in Cabinets, of which the following is a specification.

This invention relates to cabinets and is an improvement over the cabinets shown in 10 Patents Numbers 1,505,805 and 1,508,299 granted me on August 19th, 1924 and September 29th, 1924.

The principal object of the invention is to provide a cabinet of the type 15 used by persons in subjecting their bodies to the action of hot air or vapor, and which is formed of a plurality of foldable and telescoping parts in a manner to permit the structure to be transported from 20 place to place and which may be stored in a comparatively small space.

Another object is to provide a foldable bath cabinet which is simple in construction, cheap of manufacture and easy to set-up 25 when collapsed.

With these and other objects in view, the invention resides in certain novel construction and combination and arrangement of parts, the essential features of which are 30 hereinafter fully described, are particularly pointed out in the appended claims, and are illustrated in the accompanying drawing, in which:—

Figure 1 is a perspective view of my improved cabinet set-up for use.

Figure 2 is a similar view showing the device in folded condition.

Figure 3 is a vertical longitudinal sectional view on the line 3—3 of Figure 1.

Figure 4 is a fragmentary horizontal sectional view through the device when in set-up position.

Figure 5 is a perspective view of a modified form.

Figure 6 is a vertical sectional view through the form shown in Figure 5.

Referring more particularly to the drawing, especially to Figures 1 to 4 inclusive, the reference numeral 10 designates my improved cabinet in its entirety and which includes a housing 11 into which the parts about to be described are adapted to fold when in collapsed condition. The housing is open at one side as at 12, and hinged to 50 the bottom thereof as at 13 is an extension bottom 14, which when in open position is

in horizontal alignment with the bottom of the housing to form a flooring for the structure. The top wall of the housing is formed with a relatively large opening 12' 60 to permit the head of a person to be extended therethrough. The housing 11 further includes outer side walls 15 and spaced inner side walls 16. An extension section 17 is supported by the housing and includes 65 side walls 18—18 and a front wall 19 having a door 20 hingedly supported therefrom to permit ingress and egress to and from the interior of the cabinet. The side walls 18—18 telescope within the space between 70 the walls 15 and 16 of the housing when the cabinet is in collapsed condition, and for limiting the outward movement of the section with respect to the housing, I provide the walls 18—18 with inwardly projecting 75 pins 21, which enter slots 22 in the inner wall 16. The outer closed end of the slot prevents the section from being disengaged from the housing while being extended. In order to facilitate the sliding movement of 80 the section 17 with respect to the housing, I mount the section upon rollers 23, which are disposed in bifurcations formed in the bottom of the side walls. When in extended condition, the section 17 rides on to the 85 bottom extension 14. The bottom extension 14 has side flanges 24 on the opposite side edges thereof which serve to prevent lateral movement of the section when sliding in 90 either direction.

To seal the open space between the top of the housing in the front wall of the section 17, there is provided a pair of cover sections 25, formed of hingedly connected plates 26 and 27. The plates 26 are pivoted 95 upon the top of the housing as at 28 and are cut-away as at 29 so as to fit snugly about the neck to seal the opening 12' when the device is in use. The walls of the housing 11 and the section 17 are provided with vertical rows of electric light bulbs 25' which are adapted to furnish the heat for the cabinet when the same is used for subjecting the body to hot air. If desired, vapor may be introduced into the cabinet when it is 100 desired to vapor to the body.

When the parts are in collapsed condition, the section 17 telescopes within the housing so that the front wall 19 is flush with the open end of the housing, after which the bottom 14 is swung up against the wall 19 110 and fastened thereagainst by a means 30.

It is, of course, understood that the plates 27 are folded over the plates 26, after which the entire section is swung about the pivot 28, so that the sections lie within the width 5 of the housing. When in this position, the cabinet may be stored in a small space or may be convenient for transportation purposes. In Figures 5 and 6, there is shown a slight modification wherein the cabinet may 10 be folded in a more compact manner. In this form, the numeral 32 designates a housing and 33 the extension section which includes an end section 34 and an intermediate section 35 and an extension bottom 36 similar 15 to the bottom 14 of the preferred form. A head opening 37 is provided and covers 38 similar to the covers 25 of the preferred form are employed for spanning the space between the housing and the sections 34 and 20 35. The parts fold in the same manner as those of the preferred form with the exception of the intermediate section 35, which section permits the parts to fold in a housing of a less width. Electric light bulbs 33 25 are carried by the walls of the cabinet to supply the necessary heat.

What is claimed as new is:—

1. A cabinet comprising a housing open at one side and having a head opening 30 formed in a top wall thereof, an extension bottom hingedly connected to said housing, extension side walls slidably in and out of said housing, a front wall carried by said

extension side walls, a door formed in said front wall, and foldable means for closing 35 the space between said housing and the front and side extension walls, said means comprising a pair of plates pivotally mounted on said housing, and which constitute a plurality of foldable sections, adapted to be 40 folded over the top of said housing when the parts are in collapsed position to lie within the side edges of the top.

2. A cabinet comprising a housing open at one side thereof and having a head opening 45 formed in the top wall, and an extensible bottom hinged to said housing, an extensible section for telescopic relation with said housing and adapted to be supported by said extensible bottom when in set-up position.

3. A cabinet comprising a housing open at one side thereof and having a head opening 50 formed in the top wall, and an extensible bottom hinged to said housing, an extensible 55 section for telescopic relation with said housing and adapted to be supported by said extensible bottom when in set-up position, said extensible bottom adapted to be folded up against an open end of the housing to 60 hold said extensible section in telescopic condition.

In testimony whereof I have affixed my signature.

SEM ROSENTHAL.
